HAROLD B. ANDERSON AND PAUL JUSTUS, OF CLEVELAND, OHIO; BLANCHE M. ANDERSON, ADMINISTRATRIX OF SAID HAROLD B. ANDERSON, DECEASED, ASSIGNORS OF ONE-THIRD TO EDWARD C. RANNEY, OF LAKWOOD, OHIO.

SIGNALING APPARATUS.

1,178,046.

Specification of Letters Patent.

Patented Apr. 4, 1916.

Application filed March 9, 1914. Serial No. 823,289.

To all whom it may concern:

Be it known that we, HAROLD B. ANDERSON and PAUL JUSTUS, citizens of the United States, residing at Cleveland, in the county 5 of Cuyahoga and State of Ohio, have invented a certain new and useful Improvement in Signaling Apparatus, of which the following is a full, clear, and exact description, reference being had to the accompanying drawings.

This invention relates to alarms, and more particularly to alarms of the type that are intended to operate automatically to call attention to the extinguishing of a signal 15 light. An alarm of this kind is particularly useful in connection with the rear or tail light of an automobile; also in connection with the lights which are placed on the rear ends of trains and suburban cars.

It is the general object of this invention 20 to provide an automatically operating alarm of the character set forth which, while simple of construction and economical of production, is particularly efficient in operation.

A further object of the invention is to provide a construction of this character which, while including a normally open electric circuit for the alarm signal will permit of a convenient testing of this circuit 30 from time to time to ascertain whether it is broken.

Further and more generally speaking, the invention may be defined as consisting of 35 the combinations of elements embodied in the claims hereto annexed and illustrated in the drawings forming part hereof, wherein—

Figure 1 represents a perspective view of that part of the alarm signal which is located at the observer's station; Fig. 2 a vertical central sectional view through the device shown in Fig. 1; Fig. 3 a view corresponding approximately to the line 3—3 of Fig. 2; Fig. 4 a diagrammatic view of the 45 circuits whereby the signal alarm circuit is automatically closed upon the breaking of the lighting circuit; Fig. 5 a view, similar to Fig. 4, of an alarm device wherein the circuit is thermostatically controlled; and Fig.

50 Fig. 6 a view, similar to Fig. 5, of a further modification wherein the circuit including the thermostat has an electric lamp therein.

Describing by reference characters the various parts illustrated herein, 1 denotes a

casing which contains the alarm signal and 55 its operating mechanism. This casing is shown as frictionally fitting over the outer reduced cylindrical end 2 of a base 3, said base being of insulating material and being secured to the support 4 in any convenient 60 manner. In the case of an automobile, the support 4 preferably will be the dash.

The reduced end 2 of the base carries a segmental metallic plate 5 which is adapted to contact with the inner surface of the casing 65 1, as will appear more clearly from Fig. 3. The casing 1 is preferably of metal and has provided in the face which is viewed by the operator a lens 6 of any desired color, such as red. Back of the lens there is located an 70 electric lamp 7, the socket of the lamp being supported on the insulating base. Within the casing and supported on said base is an electromagnet 8, preferably comprising a pair of cores and coils and having an armature 9 connected by a flat curved spring 10 with a post 11. When the magnet is de-energized, the armature is adapted to engage a contact 12 on an L-shaped post 13 which preferably rests upon the metallic base of 80 the lamp 7, both the lamp base and the post 13 being conveniently connected to the insulating base by means of a common screw 14. 15 denotes a ring which is mounted within the casing 1, being conveniently supported 85 by a pair of posts 16 from the base 2, 3.

17 denotes a curved spring switch arm connected at one end to the casing 1, between the ring 15 and the casing, and having its other end provided with a push button 18. 90 The switch arm 17 will preferably be concaved whereby, when out of operation, it will lie against the inner surface of the casing.

19 denotes a post from which the coil 95 winding 20 extends, the opposite end of the winding extending to the post 21 and to the plate 5.

22 denotes a conductor extending from the post 13 to one of the posts 16, whereby the 100 conductor is in electrical contact with the ring 15.

In the construction illustrated in Figs. 1 to 4 inclusive, it is contemplated that the alarm shall be used in connection with the 105 tail lamp of an automobile or the rear lamp or lamps of a car or train, to light the lamp 7 and illuminate the lens 6 when the former

lamp or lamps are extinguished. The way in which this result is accomplished will be apparent from an inspection of Fig. 4, wherein a rear lamp is indicated at 23 and the batteries or other source of electric energy at 24.

The tail lamp circuit will now be described.

20 denotes the conductor extending from one side of the battery (or other source of electrical energy) through a switch 25 to and through the lamp 23, thence around the cores of the electromagnets 8 and through the conductors 26 and 27 back to the battery. It will be evident that, as long as the 15 circuit through the lamp 23 is closed, the magnets 8 will be energized and the armature 9 be held against the cores thereof. Should, however, this circuit be broken, the spring 10 will throw the armature against 20 the contact 12, establishing the alarm signal circuit, whereupon current will flow through the circuit including the conductor 28, lamp 7, contact 12, armature 7, conductor 29 and conductor 27, back to the battery.

25 Should the operator desire to test the alarm signal circuit, it is only necessary for him to press inwardly upon the push button 18. This will bring the switch arm 17 into engagement with the ring 16, whereupon the alarm signal circuit through the lamp 7 will be closed through the switch 25, conductor 29, lamp 7, ring 16, switch arm 17, casing 1, plate 5, and conductors 26 and 27. Owing to the small resistance of this 35 circuit, sufficient current will flow through this circuit to illuminate the lamp unless the circuit be broken in some manner, as by the breaking of the lamp filament.

It will be seen that three electrical circuits 40 are provided, one of which includes the tail or rear lamp and the windings of the electromagnet, one of which includes the armature of the electromagnet and the alarm device, while the third is a test circuit which 45 includes the alarm device but includes neither the electromagnet windings nor the armature.

In Fig. 5, there is shown a modification of the invention wherein the lamp, the extinguishment of which is to be indicated by the alarm, is not necessarily an electric lamp. In this modification, the lamp 30 may be an oil lamp, the flame whereof is arranged to heat a thermostatic switch 31, 55 so constructed that, by the heating of the thermostat to a certain temperature, one end thereof will engage a contact 32. Assuming that the lamp 30 is burning properly, the current will flow from the source of electrical energy 24 through conductors 33, 34, contact 32, switch 31, conductor 20^a, around the cores of the electromagnets 8 and back to 24 through the conductor 35. The 60 alarm circuit will then be broken by the armature 9 being retained against the

cores of the electromagnets. Assuming, however, that the flame of the lamp 30 is extinguished, or that it burns so low as to be ineffective, the cooling of the thermostat will cause the foregoing circuit to be broken 70 by the flexing of the thermostat away from the contact 32. This will deenergize the magnets 8, and the alarm circuit will then be established as, heretofore explained, through conductors 33, 29^a, lamp 7, contact 75 12, armature 9, conductor 28^a and conductor 35. To test the signal circuit it will be necessary only to push in the button 18, whereupon this circuit will be established through conductors 33, 29^a, lamp 7, ring 16, 80 switch 17, casing 1, block 5, and conductors 36 and 35.

In Fig. 6 there is shown a still further modification of the invention wherein the circuit of the electric lamp which is to be 85 protected is thermostatically controlled and wherein the alarm signal circuit will be automatically closed not only as by the breaking or deterioration of the filament of the electric lamp, but by the substantial ineffectiveness of the lamp which heats the thermostat. In this embodiment, the current from the source of electrical energy 24 flows to the electric lamp 23^a through the conductor 37, contact 32^a, thermostat 31^a and 90 conductor 38, thence through conductor 20^b, around the cores of the magnets 8, and through conductors 39 and 40 back to 24. Assume, however, that the circuit including the lamp 23^a is broken, as by the breaking 95 or deterioration of the lamp filament or through the lowering or extinguishing of the lamp 30. In such event, the circuit through the alarm signal will be established through conductor 41, lamp 7, contact 12, 100 armature 9, conductor 28^b and conductor 40. 105

The alarm circuit may be tested in the same manner as in the two preceding embodiments of the invention, viz: by pressing inwardly upon the button 18, whereupon the 110 circuit will be established through conductor 41, lamp 7, ring 16, switch 17, casing 1, block 5, and conductors 42, 39 and 40.

In all three embodiments of the invention disclosed herein two circuits are provided, 115 one of which operatively includes and is controlled by the lamp to be observed and the other of which includes the signal alarm, with connections whereby the second circuit will be automatically closed through the opening of the first circuit, and vice versa; also that, in all three embodiments of the invention a testing circuit including the alarm signal is provided, the testing circuit being in shunt with the first circuit. 120

Having thus described our invention, what we claim is:—

1. In an apparatus of the character set forth, the combination of an electric circuit, a lamp therein, a second electric circuit, an 125

- alarm signal therein, connections whereby the alarm signal circuit will be closed through the opening of the first mentioned circuit, a test circuit for the alarm signal, 5 and a source of electrical energy common to the first and last mentioned circuits.
2. In an apparatus of the character set forth, the combination of an electric circuit, a lamp therein, a second electric circuit, an 10 alarm signal therein, connections whereby the alarm signal circuit will be closed through the openings of the first mentioned circuit, and a test circuit for the alarm signal.
- 15 3. In an apparatus of the character set forth, the combination of an electric circuit, said circuit including a lamp and the winding of an electromagnet, a second electric circuit including an alarm signal and the 20 armature of said magnet and adapted to be closed by the movement of the armature away from said magnet, a manually operated test circuit including the alarm signal, and a source of electrical energy common 25 to said circuits.
4. In an apparatus of the character set forth, the combination of an electric circuit, said circuit including a lamp and the winding of an electromagnet, a second electric 30 circuit including an alarm signal and the armature of said magnet and adapted to be closed by the movement of the armature away from said magnet, and a manually operated test circuit including the alarm signal, 35 nal.
5. In an apparatus of the character set forth, the combination of an electric circuit,
- a second electric circuit, an alarm signal therein, connections whereby said alarm signal circuit will be closed through the opening of the first mentioned circuit, and a test circuit for the alarm signal. 40
6. In an apparatus of the character set forth, the combination of an electric circuit including a lamp and an electromagnet, a second circuit including an alarm signal and the armature of said magnet and adapted to be closed by the movement of the armature away from the magnet, a casing for the electromagnet and the alarm signal, a 45 switch carried by the casing, a testing circuit for the alarm signal including said switch, and a source of electrical energy common to all of said circuits. 50
7. In an apparatus of the character set forth, the combination of an electric circuit including a lamp and an electromagnet, a second circuit including an alarm signal and the armature of said magnet and adapted to be closed by the movement of the 55 armature away from the magnet, a casing for the electromagnet and the alarm signal, a switch carried by the casing, and a testing circuit for the alarm signal including said switch. 60
- In testimony whereof, we hereunto affix our signatures in the presence of two witnesses. 65
